UNITED STATES PATENT OFFICE.

HIRAM S. MAXIM, OF PARIS, FRANCE.

GAS-MOTOR.

SPECIFICATION forming part of Letters Patent No. 291,065, dated January 1, 1884.

Application filed January 16, 1883. (No model.)

To all whom it may concern:

Be it known that I, HIRAM S. MAXIM, a citizen of the United States, at present residing in Paris, in the Republic of France, have 5 invented certain new and useful Improvements in Gas-Motors, of which the following is a specification, reference being had to the drawings accompanying and forming a part of the same.

- 10 My invention relates to motors operated by the explosion of mixed charges of air and gas under a piston, connected with suitable mechanism for converting and utilizing the power developed by the explosions. The main objects of the invention are to produce a cheap, compact, and durable engine, and one which will run at a high rate of speed and develop a great amount of power for a given quantity of gas consumed.
- 15 The general and distinguishing features of the invention are, first, the combination, in an engine of the kind described, of two cylinders—a working and exhaust cylinder—the latter of relatively large size, and both open to a vacuum-chamber with connected pistons working in the same, these and the remaining parts of the engine being so constructed that the larger or exhaust piston will produce a partial vacuum and remove at the end of each stroke the products of combustion from the smaller or working cylinder; secondly, the combination, with the working-cylinder, of a pump for forcing in charges of air and gas, the piston of which is raised by a cam and forced downward by 20 the combined action of gravity and a spring, whereby the charge is thrown into the working-cylinder very quickly; thirdly, an igniting apparatus constructed in such manner that the igniting-flame is thrust at once into the exploding-chamber; and, lastly, the invention involves certain other features of novelty in the construction and arrangement of parts of the engine, the nature of which will be more fully hereinafter set forth.
- 25 In the accompanying drawings, Figure 1 represents in vertical central section my improved motor complete. Fig. 2 is a side elevation of the same, showing the exhaust-valve in section; Fig. 3, a detail of the governing 30 or regulating mechanism; Fig. 4, a horizontal

section on a reduced scale on line xx of Fig. 1.

Similar letters indicate corresponding parts in the several figures.

A and B are two cylinders, placed in line one above the other. A is the working-cylinder of the engine; B, a cylinder of larger diameter, designed as a vacuum-cylinder.

A' is a piston working in cylinder A; B', a larger piston, working in cylinder B. These pistons are both mounted on or operated by the same rod, C, and may be cast in a single piece when so desired. Cylinder A is inclosed in the usual water-jacket, D, through which a circulation of water is maintained for cooling the cylinder, a and a' being respectively the inlet and outlet for the water. The upper portion of the jacket D is separated from the water-space below, forming a chamber, D', above and around the open end of the working-cylinder. The cylinders A and B are separated by a plate, b , in which is an annular valve, b' , opening upward.

X is an ordinary safety-valve in cylinder A.

E is the crank-shaft, turned by rod C; E', the fly-wheel, and E'' the pulley-wheel containing the governor mechanism.

Communicating with the bottom of cylinder A is the force-pump F, for introducing charges of gas or gas and air combined. The piston f of pump F is on a rod, F', the upper end of which connects with the open or slotted plate G. Through this plate passes the crank-shaft E, and a guide-wheel, e , fixed to the frame of the engine, holds the plate in position, permitting it to move freely up and down.

On the crank-shaft E, and keyed to it, is a sleeve, e' , capable of a to-and-fro movement.

G' is a cam carried by sleeve e' and d , a wheel carried by the plate G. A stout spiral spring, S, connected to the frame of the engine and to the rod F', tends to draw the latter downward.

In the pulley-wheel E'' are hung governor-weights H H', with arms H' H'', that are connected with the sleeve e' . Spiral springs s' s' connect the governor-weights, and tend to draw them together.

The principle of operation of the governor is to regulate the number of explosive charges admitted to the working-cylinder rather than

the quantity or quality of each charge. It will be understood, then, that when the engine is first started, or is running at slow or normal speeds, the force of springs $s's'$ keeps the weights $H H$ in such position that the cam G' is held over under the wheel d , so that a charge of gas or gas and air is admitted to the cylinder A at every revolution of the crank-shaft. Should the speed run up, however, as by lightening the load on the engine, weights $H H$ are thrown outward by centrifugal force against the force of springs $s's'$, the sleeve e' is by this means shifted, and the cam G carried out of line with the wheel d . No charge will in consequence be delivered to the working-cylinder until the normal speed is again reached.

Entering the lower part of the cylinder A is an exploding-piston, I , that is operated by a bell-crank lever, h , connected by a rod, h' , with the strap of an eccentric, i .

J is a flame-chimney of ordinary construction, in which a flame is kept constantly burning. A passage is formed from this chimney through the casing or cylinder, in which works piston I , as shown in Fig. 4. The piston I consists of a solid portion, i' , and a chambered end with openings on both sides, as shown in Figs. 1 and 4, so that when it is drawn out it carries with it a charge of gas which is ignited by contact with the flame j . On the return of the piston the burning charge in its chambered end is thrust suddenly into the space beneath the piston A' , thus igniting the charge therein. Above the plate b is a recess, K , into which the piston B' partly enters when in its lowest position.

K' is an exhaust-passage containing a check-valve, k , connected with this space and serving to carry off the products of combustion withdrawn from cylinder A .

In the bottom of cylinder A is a large valve, L , opening inward for admitting air into the cylinder A when the piston A' has reached a point above a line of perforations, m , leading into the space D' . With valve L a spring may be used for controlling its action.

The valve mechanism connected with the pump is as follows: M is a valve composed of a short cylinder, the head of which rests upon a seat, n . A line of perforations, t , is formed in the side of the cylinder near the head, and a spindle, o , connected to the valve, extends through the passage of communication between the cylinder A and the pump-cylinder. A spiral spring, p , is used to keep valve M closed, and a cap, t' , is screwed over the end of the spindle to prevent leakage. Into the passage n' lead two valves, one, as r , an air-valve with a lid, r' , or similar means for closing it, the other, as v , a gas-valve controlling communication with a suitable gas-supply through a pipe, v' . As it is desirable to vary the amount of gas admitted to the engine, I use an ordinary cock-valve consisting of a cup, w' , with an opening that registers with the pipe v' . A handle, x , turns this cup and closes

off more or less the passage. A pointer, x' , may be attached to the handle x and a scale cut on the valve-casing for indicating the amount of gas that is being admitted for a given position of the handle x .

For maintaining the necessary lubrication of the crank and shaft, I use oil-cups $T U V$. The cups $T U$ supply oil to the bearings. The cup V has a wick, V' , that is touched by a cup, W , at each revolution of the crank. A drop of oil is thus taken off at each contact.

Other details of construction will be indicated in the following description of the operation of the engine. The crank-shaft being rotated by hand or otherwise in the direction indicated by the arrow, the pump F is operated, being filled with a mixture of gas and air through the valves r and v . When cam G' , which causes this, has reached a point where the wheel d drops off from it, the combined action of the weight of the piston f and the spring S will force the mixed gases through valve M into the cylinder. The valve M being cylindrical in form and provided with a number of holes, the gases entering are driven with great force through these holes, and its mixture with the air in the cylinder is quickly accomplished.

The cam is so adjusted on the crank-shaft that the pump-piston falls at the moment when the working-piston A' has passed far enough into the cylinder to close off the openings $m m$. When the gas and air are both in the cylinder and the piston A' has reached the point shown in the drawings, the air and gas beneath it in the cylinder A will have been compressed about forty pounds to the square inch. At this moment the flame is thrown into this chamber by the action of the eccentric i , bell-crank lever h , and exploding-piston I .

When the explosion takes place, the pressure produced in A will be about one hundred and seventy-five pounds to the square inch; but complete combustion will not take place until the piston has traveled nearly its whole stroke from the fact that the gases do not have time enough to dispose of their heat, and perfect combustion cannot take place except the gases have some means of disposing of their heat. Therefore a high pressure is maintained during nearly the complete length of the stroke.

When, however, the piston has passed over the openings $m m$, the exploded gases instantly escape into the chamber D' . As the piston B' is attached to the same rod that A' is, a partial vacuum will be produced in D' and in cylinder B , and the gases escaping from the smaller cylinder not being able to fill this vacuum, fresh air is drawn in through the large valve L . The piston B' being considerably larger than the piston A' , the quantity of fresh air drawn in at L will be sufficient to remove all the exploded gases completely from the smaller cylinder. When the piston A' has again covered the openings $m m$ in its upward stroke, the piston of the pump F again falls, and a fresh charge of explosive gases is forced

115
120
125
130

into the space below the piston. The piston descends, compresses the gases, and the explosion takes place as before. The valve L being very large and opening freely inward, 5 admits of a very rapid action of this motor. The circulation of water in the jacket D prevents destructive heating of the apparatus.

The cubic capacity of the pump F should be about one-sixth part of that of the cylinder 10 A, so that if the pump F should be completely filled with gas the charge in the cylinder A would be six of air to one of gas. To effect this the air-valve r will have to be closed, then at each stroke of the pump the pump will be 15 filled completely with gas, the index-valve being opened sufficiently to admit of this. If, however, it is desired to put a less quantity of gas in at each stroke, the index-valve is partially closed and air is admitted at r. 20 If the quantity of air and gas admitted be equal, then the working-cylinder would contain at each explosion a mixture of twelve parts of air to one of gas. By mixing a portion of the air with the gas before it enters the 25 exploding-cylinder, and then passing it with great rapidity through the perforations in the sleeve of the valve M, the mixing is performed quick enough to admit of a very high speed of the engine. The gases pass from the chamber 30 D to the chamber K through the annular check-valve b', and when the piston B' descends these gases are forced out through the exhaust check-valve k. Of course it would be possible to dispense altogether with the check-valve b' 35 and to construct the pistons both in one piece. This would admit of making the engine somewhat shorter, but it would also require that the piston B' should be somewhat larger, in order to suck all the gases out of the smaller 40 cylinder.

In other applications I have described more fully and claimed this and other improvements not embodied in the present claims.

I am aware that two connected cylinders or 45 a cylinder having one portion of greater diameter than another, and connected pistons uniting therein, have been heretofore used, and such, therefore, I do not broadly claim.

Having thus described my invention and the 50 most practicable manner in which the same is or may be carried into effect, what I claim as new is—

1. An air or gas engine comprising, in combination, the following instrumentalities, to 55 wit: a working-cylinder and means for exploding therein charges of gas and air, a piston impelled by such explosions, a vacuous chamber brought into communication with the working-cylinder by the movement of the piston, a valve for admitting air into the cylinder 60 when connected with the vacuous chamber, and means for introducing explosive charges into the cylinder, these parts being constructed and combined for co-operative action in sub- 65 stantially the manner set forth.

2. In a gas-engine, the combination, with the

working-cylinder and piston, of a vacuum-cylinder of greater capacity, a piston working therein, and an intermediate recess or chamber with which the working-cylinder is brought 70 into communication by the withdrawal of its piston, whereby at the end of each stroke the gases are withdrawn from the working-cylinder, in the manner described.

3. The combination, with the working-cylinder of a gas-engine, of a pump for introducing explosive charges into said cylinder, means for positively raising the piston of the pump and then disengaging it, and a spring for forcing it downward, all as set forth. 75

4. The combination, in a gas-engine, of the working and vacuum cylinders connected in the manner described, the pistons working in said cylinders, and the intermediate chambers of communication at and around the ends of 85 said cylinders, as described.

5. The combination, with the working and vacuum cylinders and pistons contained therein, of intermediate chambers of communication at or around the ends of the cylinders, 90 the working-cylinder being perforated in substantially the manner described, whereby communication is established between the two cylinders through said intermediate chambers on the partial withdrawal of the pistons, as and 95 for the purpose set forth.

6. The combination, with the working and vacuum cylinders and pistons contained therein, of chambers or vacuous spaces located around the ends of and between said cylinders, and exhaust connected with the said chambers, as and for the purposes set forth. 100

7. The combination, in a gas-engine, of a working cylinder and piston and a vacuum cylinder and piston, an automatic air-check 105 valve opening into the working-cylinder, and an exhaust-valve opening outward, these parts being combined in substantially the manner described.

8. The combination, with the working-cylinder of a gas-engine, of a pump for introducing charges of air and gas into the cylinder, and a valve located between the cylinder and pump, and provided with a number of perforations, through which the air and gas are forced when 115 the valve is open, as and for the purpose set forth.

9. The combination, with the working-cylinder, of the pump F, the perforated valve M, with air and gas inlet valves, and means for 120 controlling the same, as and for the purpose specified.

10. The combination, with the pump F, piston-rod f, and plate G, of spring S and cam G', all as set forth. 125

11. The combination, with the working-cylinder, of the chambered piston, the flame-chimney, a bell-crank lever connected with the piston, and an eccentric for operating the bell-crank lever, all as set forth. 130

12. The combination of the bell-crank lever h, rod h', eccentric i, piston I, containing a

chamber at its inner end, and the flame-chimney J, these parts being constructed and arranged in such a manner that the piston I thrusts the flame directly into the interior of 5 the working or explosion cylinder, in the manner described.

13. The combination, with the working-cylinder, of an induction-valve, L, perforated

valve M, pump F, and valves connecting therewith, and exhaust-valve, these parts being 10 constructed in the manner specified.
